UNITED STATES PATENT OFFICE.

GEORGE ALDWORTH, OF LONDON, ENGLAND, ASSIGNOR TO CHARLES NESSLER, OF LONDON, ENGLAND.

ADJUSTABLE SUPPORT.

1,201,789.

Specification of Letters Patent.

Patented Oct. 17, 1916.

Application filed March 18, 1915. Serial No. 15,262.

To all whom it may concern:

Be it known that I, GEORGE ALDWORTH, subject of the King of Great Britain and Ireland, residing at London, W., England, have invented certain new and useful Improvements in Adjustable Supports, of which the following is a specification.

My invention relates to improvements in apparatus for the support and suspension of hair waving devices employed for the purpose of waving hair on the human head.

In apparatus of this kind it is usual to suspend the hair waving devices from the ceiling but this implies in practice that the patient must go to the establishment of the hair waver in order to have her hair treated.

My invention relates to an apparatus which can be easily erected, easily taken to pieces and easily transported from one place to another, so that the hair waving operation may be performed at the home of the patient or at any other convenient place.

My apparatus is illustrated in the accompanying drawings, in which:

25 Figure I shows the complete apparatus when mounted and in use. Fig. II illustrates in part elevation and part section what I term a "gallows". Fig. III is a plan view of the clipping frames. Fig. IV is a 30 half side elevation, half vertical section of the clipping frames shown on a larger scale than is the case in Fig. III. Fig. V is a part plan, part horizontal section of the clipping frames also on a larger scale. Fig. VI is a section on the line *a*—*b* of Fig. II. Fig. VII is a section on the line *c*—*d* of Fig. IV.

Referring now to these figures, 1 is a base plate by means of which my apparatus can 40 be attached by a clamp, such as 2, to a stool or table 3. Upon this base plate is a socket 4 into which fits the lower end of the main length 5 of my standard. This main length is tubular for the reception in a telescopic 45 manner of the upper length 6 of the standard. The upper length can be slid more or less into the main length and bound in any desired position by the thumbscrew 7 which may either bite upon the length 6 or may 50 penetrate orifices 8 therein. By this means

the height of the upper part of the gallows may be adjusted to suit the operation to be carried on.

9 is the top-rod of the gallows fitted at one end with the elbow junction 10 whose 55 vertical part may be slipped over the upper end of the length 6 and bound in position by the thumbscrew 11.

12 is a stay hung loosely from the sliding clip 13 so that it may swing therefrom. In 60 the operation of mounting the gallows, this clip 13 is slid along the top-rod loosely, while at the same time the stay 12 is brought to the position shown in Fig. I and caused to engage the upper length 6 as shown in 65 Fig. II where it will be seen that a pin 14 penetrates an orifice in the upper length 6. The thumbscrew 15 is now tightened so that the parts 6, 9 and 12 are rigidly affixed and 70 form a strong triangular bracing. From 70 the free extremity or other convenient part of the top-rod 9 depends the hanger-rod 16, the connection between the hanger-rod and the top-rod being effected by the sleeve 17 formed integral with the hanger-rod and 75 slid over the free end of the top-rod. A thumbscrew similar to 15 may be employed on the sleeve 17. Near the lower end of the hanger-rod 16 are two orifices 18, 19 through which pass the horizontal rods 20, 80 21 of the clipping frames. At the outer extremities of the horizontal rods 20, 21 are attached the curved rods 22, 23 by being passed through and soldered in the sleeves 24, 25. Thumbscrews as 24^a may be employed for further binding the curved rods (when they are round) to the horizontal rods. Thumbscrews on the hanger-rod 16 may be employed as shown in Figs. III and 85 V to bind the horizontal rods 20, 21 in position. It will be seen that these horizontal rods together with the curved rods attached to them are in different planes, so that they can be slid to right or left as desired.

26, 27 are two electric heaters employed 95 in the hair waving process and these are suspended by cords 28, 29 from clips 30, 31 of any convenient kind attached at any convenient positions either to the curved rods 22, 23 or to the horizontal rods 20, 21. The 100

cords 28, 29 pass through orifices in the clips 30, 31 upward through the rings 32, 33 which are attached to the counterweights 34, 35, then over pulleys in the suspension block 36 and downward to the counterweights 34, 35. These counterweights act precisely in the well known manner of similar counterweights in rise-and-fall fittings of electric lamps. The suspension block 36 is shown 10 in detail in Fig. VI where it will be seen that it carries eight pulleys over each of which a cord sustaining a heater or other hair waving device may pass. In this suspension block it will be seen that each pulley 15 is supported in a stirrup as 37 riveted to a base plate 38 which base plate is riveted to the short sleeve 39 sliding over the top-rod 9 to which it may be bound by thumbscrews 40 in a well known manner. In Figs. I and 20 VI the top-rod is shown as having orifices 41 in its upper part to receive thumbscrews. As a matter of fact however in Fig. VI 40 is a headed spring-bolt of a well known kind instead of being a thumbscrew, but of course 25 a thumbscrew can be used as an equivalent. In a similar way wherever I refer to a thumbscrew in this specification a spring-bolt such as is shown in Fig. VI may be employed. 30 42 is a thumbscrew (there may be two of them) which serves to bind the horizontal rods 20, 21 in position on the hanger-rod 16. This is shown separately in Fig. VII. For convenience of drawing these thumbscrews 35 are omitted in Fig. I.

43, 44 are the leads connecting the electric heaters 26, 27 with the source of electrical energy. They are shown simply diagrammatically for the current may be led to the 40 heaters in any desired way. For example the leads 43, 44 might constitute the suspending cords 28, 29, or they could be brought to the heaters in any other convenient way.

45 I desire it to be understood that although the main length 5 is preferably tubular for the purpose specified the other length and the rods may be either tubular or solid. For lightness I prefer to make all these 50 parts tubular. The base plate 1 and the socket 4 may be integral with the main length. To prevent injury to the table or stool to which the base plate is attached a disk of leather or the like 45 may be employed. Instead of fixing the sliding clip 13 to the top-rod and causing the pin 14 to engage the upper length I may reverse these and put the sliding clip 13 upon the upper length 6 and cause the pin 14 to engage an 60 orifice in the top-rod 9.

Two heaters or waving devices are shown in Fig. I, but it is sometimes necessary to employ a large number at the same time upon a single patient. A number of sus-

pension blocks therefore commensurate with 65 the number of such heating or waving devices may be used. They may have any desired number of pulleys attached.

In Fig. II, I have shown the devices which I prefer to employ but it is quite 70 unnecessary for me to specify what parts are brazed or otherwise joined together at the junctions as all such junctions are well known to mechanics. Equivalents for many of these parts are also well known to mechanics. 75

I have hereinbefore referred to a clamp for fastening the base plate to a stool or table but it will of course be understood that if the base plate be sufficiently extended, 80 particularly in the direction of the free end of the top-rod, such clamp will be unnecessary and the base plate in that case might rest on the floor.

Having thus described my invention what 85 I claim as new and desire to secure by Letters Patent is:—

1. In apparatus of the class described, the combination of a standard and a horizontally extending top-rod mounted on said 90 standard, a hanger-rod depending from said top-rod, horizontal rods slidably mounted on said hanger-rod and each provided with clip-supporting bent frames.

2. In apparatus of the class described, the combination of a standard and a horizontally extending top-rod mounted thereon, a hanger-rod depending from said top-rod, oppositely projecting horizontal-rods adjustably mounted on said hanger-rod, and 100 clip-supporting frames secured to each of said horizontal-rods and extending inwardly upon opposite sides thereof toward said hanger-rod.

3. In apparatus of the class described, 105 the combination of a standard and a top-rod mounted thereon so as to project horizontally, a hanger-rod depending from said top-rod and clip-supporting rods mounted thereon, clips mounted on said horizontal-rods, pulleys mounted on said top-rod, suspending cords passing over said pulleys and provided with counter-weights each having a guide-eye thereon, the said suspending cords passing through its respective clip 110 and eye on its counter-weight.

4. In apparatus of the class described, the combination of a standard, a horizontally projecting top-rod mounted thereon, a gang 120 of pulleys having a frame in which they are mounted and said frame being slidably mounted on said top-rod, a hanger-rod depending from said top-rod, clip-supporting mechanism mounted on said hanger-rod, clips on said mechanism, and a set of suspending-cords passing over said respective pulleys and engaging said respective clips.

5. In apparatus of the class described, the

combination of a support, horizontal-rod
mounted on said support and having capac-
ity of endwise adjustment in the horizontal,
a horizontally disposed bent rod mounted
5 upon each of said adjustable horizontal rods
with the bent parts thereof directed in-
wardly with respect to said support, and
clips mounted on said bent rods.

In witness whereof I have signed my
name to this specification in the presence of 10
two subscribing witnesses.

GEORGE ALDWORTH.
